UNITED STATES PATENT OFFICE.

EMMIT G. LATTA, OF SYRACUSE, NEW YORK, ASSIGNOR TO FIRST TRUST AND DEPOSIT COMPANY, ADMINISTRATOR OF SAID EMMIT G. LATTA, DECEASED.

TYPEWRITING MACHINE.

Original application filed March 18, 1920, Serial No. 366,807. Divided and this application filed July 17, 1924. Serial No. 726,632.

To all whom it may concern:

Be it known that I, EMMIT G. LATTA, a citizen of the United States, residing at Syracuse, in the county of Onondaga and 5 State of New York, have invented a new and useful Improvement in Typewriting Machines, of which the following is a specification.

This invention relates to typewriting machines and particularly to improvements in line space mechanisms therefor.

The present invention is a divisional one from my copending application for improvements in typewriting machines Serial No. 15 366,807 filed March 18, 1920.

One object of the invention is to improve typewriting machines by making a line space mechanism and its attachments more compact without lessening its efficiency, to locate such parts in desirable positions for use, and to make them so that they can be condensed, or reduced in dimensions for encasing the machine when traveling. The improvements are especially desirable for collapsible or portable typewriting machines, such, 20 for instance, as that disclosed in my copending application Serial No. 319,609, filed August 25th, 1919, but the invention is not restricted to use on portable typewriters, and 25 can be used on standard machines.

Other objects are to adapt a carriage with an ordinary rotary platen to take wider paper than others of no greater total length, and to do this with platen knobs operatively 30 located at suitable distances from the ends of the carriage; also to accomplish this result in a construction having a horizontally swinging line space lever of approved form and location, and a line space adjusting device in 35 convenient positions for use.

Another object is to cause the paper shelf to swing forwardly when the carrying case is closed and thus shorten the machine and at the same time unlock the supporting 40 bracket for the line space lever so that said bracket will automatically assume a lower position as the case is closed.

Other objects are to provide a line space

mechanism which is detachably secured to 50 and removable with the platen, or which may remain on the carriage as may be desirable or necessary; also to provide a line space mechanism by which the platen can be rotated with the minimum effort and in 55 which the line space pawl and other parts are located so as to permit the use of paper wider than the platen without interference therewith; and to improve the construction 60 of typewriting machine line space mechanisms in the other respects hereinafter described and set forth in the claims.

In the accompanying drawings:

Fig. 1 is a side elevation partly broken away of a portable typewriting machine embodying the invention. 65

Fig. 2 is a front elevation of the platen carriage removed from the machine, and showing the parts in their operative positions. 70

Fig. 3 is a top plan view thereof.

Fig. 4 is a sectional elevation thereof on line 4—4, Fig. 3.

Fig. 5 is a similar view thereof, but with the parts occupying the inoperative positions which they assume when the machine is encased for transportation. 75

Fig. 6 is a front elevation, detached, of the line space lever bracket with the ratchet 80 detent thereon.

Fig. 7 is a fragmentary sectional end elevation on line 7—7, Fig. 3.

Fig. 8 is an elevation of the outer end of the line space lever bracket.

Fig. 9 is a similar view of the inner end 85 thereof, and showing one end of the ratchet detent spring in engagement with the carriage rack bar.

Fig. 10 is a longitudinal sectional elevation of the platen and line space mechanism, 90 showing the parts of the platen shaft in their collapsed or inoperative positions.

Fig. 11 is a fragmentary view similar to Fig. 10 but showing the parts of the platen shaft in operative position. 95

Fig. 12 is a plan view of the sheet metal stamping used for making the line space adjusting device.

Fig. 13 is a horizontal plan view of the line space adjusting device, showing by full lines its position for a three line space adjustment, and by broken lines the two line 5 and single line space positions.

Figs. 14, 15, and 16 are sectional elevations of the line space adjusting mechanism on line 14—14, Fig. 3 and showing the parts in different positions.

10 Fig. 17 is a side elevation detached, of the line space lever.

In this application the invention is shown and described in connection with a portable typewriting machine of the sort disclosed in 15 my copending application above mentioned. In this machine all the operative parts are mounted on a hollow main frame A which forms the lower part of the enclosing case for the machine. The bottom 11 of this 20 frame has front and rear portions extending at an obtuse angle to each other to enable the frame to be supported either in an inclined or horizontal position. B represents the upper or cover part of the enclosing case. The edges of the side walls 18 thereof are 25 shaped to fit the bent upper and lower edges of raised panels 19 on the sides of the main frame. When the cover is in the position shown in Fig. 1 all the operative parts of the 30 machine are disposed between two parallel planes indicated by the lines a—b and c—d. The cover is adapted to be removed and placed in an inverted position on a support and the frame A is placed on the cover with 35 the lower edges of the panels 19 resting on the edges of the sides 18 of the cover. The cover then forms a base by which the machine is supported in an inclined operative position, and the planes a—b and c—d will 40 incline upwardly and rearwardly at the angle represented by the dotted line a—b in Fig. 4.

20 represents the usual carriage guide track, which, as shown, is secured at its ends 45 to the side walls 14 of the main frame. The carriage C as usual comprises a track bar 25 movable along the guide track 20 on balls 26, and end plates 27 and 28 rigidly secured to the opposite ends of the bar 25. The end 50 plates are provided with bearing seats for the shaft of the platen D. E, E represents the usual paper feed rolls, F is the carriage escapement wheel, G the rack bar and H the pinion meshing with the rack bar for controlling the letter space movements of the carriage. The end plates 27 and 28 of the carriage C are substantially alike, each having a laterally offset recessed part 29 and upright front and rear extensions 30 and 31 respectively. A scale bar 35 connects the two front extensions 30.

The end wall 36 of each recessed part is provided with an upwardly and rearwardly extending, open ended slot 37 and the circular bottoms of these slots are enlarged to

form bearing seats for the shaft of the platen D. The bottoms of the recesses 29 are concentric with these seats. A carriage release lever 40 pivotally mounted inside of the end plate 27 on the end wall of the recess 70 29 thereof, and an arm 41 similarly pivoted on the end plate 28, are secured at their rear ends to the rack bar G, so that the rack bar G may be lifted out of mesh with its pinion H to permit the carriage C to be set back for 75 starting a new line by depressing the front end 42 of the release lever 40.

The platen D comprises the usual hollow cylindrical core 45 of wood or the like, an outer resilient covering 46 and end disks 47, 48 secured to the opposite side of the core by screws 49 and mounted on a platen shaft J.

The platen shaft J, is telescopic, comprising a middle tubular section 50 and opposite end sections 51, 52 formed by rods adapted to slide in the tube 50 from outer operative positions to inner inoperative positions. The tube 50 is provided near its opposite ends with longitudinal slots 55, and cross pins 57 extending through the inner ends of the end sections 51, 52 and entering the slots 55, guide and limit the movements of the end sections in the tube. Finger wheels or knobs 58 and 59 are secured to the outer ends of the end sections. The operative positions of these finger wheels and of the end sections of the shaft J are shown in Figs. 2, 3, and 11, also by dotted lines in Fig. 10. In this position the finger wheels 100 are located outwardly away from the end plates of the carriage where they can be conveniently grasped and operated. They are held in this position with the pins 57 against the outer ends of the slots 55, by a 105 helical spring 60 in the tube 50 and engaging the inner ends of the end sections.

When it is desired to reduce the width of the machine the end sections 51, 52 of the platen shaft are pushed inwardly by 110 means of the finger wheels to the positions shown in Fig. 10 and there locked by turning the finger wheels in opposite directions to cause the cross pins 57 to enter lateral seats (not shown) at the inner ends of the 115 slots 55, in which they will be retained by the pressure of the spring 60.

The platen D is preferably removable from the carriage and in the preferred construction for this purpose the end sections 51, 52 of the platen shaft are flattened or notched on opposite sides as at 63, Figs. 10 and 11, so that if the end sections are pressed inwardly until these notches 63 register with the slots 37 in the carriage end plates and turned to align the notches 63 with the slots, then the shaft can be removed through the slots 37. In the normal position of the end sections of the shaft, the engagement of their cylindrical por- 125 130

tions in the circular bearing seats prevents accidental disengagement of the platen.

The line spacing mechanism includes a ratchet wheel 65 which is loosely journalled 5 on the left hand end of the tube 50 which forms a portion of the platen shaft, between the adjacent end disk 48 of the platen and a screw sleeve 67 which is screwed on the threaded outer end of the tube 50. The 10 ratchet wheel can be turned independently of the platen, but is held in frictional connection therewith by suitable means, such as a spring washer 66 between the ratchet wheel and platen end plate and having 15 radial spring arms 67^a, see Figs. 14-16. The sleeve 67 has an inturned outer end adapted to engage the extreme end of the tube 50 to prevent the ratchet wheel from being clamped too tightly. The ratchet wheel 65 20 is therefore releasably or frictionally held by the washer 66 in such manner as to permit it to turn with, or independently of the platen when so desired.

The ratchet wheel 65 is provided with 25 an annular series of holes 70, and a locking pin 71, rigidly secured to the end section 52 of the platen shaft and is adapted when said section is moved to its outer operative position, to enter one of the holes 70 and 30 lock the ratchet wheel to the platen so that the rotation of the ratchet wheel will then be imparted to the platen. In the construction shown in the drawings the locking pin 71 is rigid with a sleeve 72 which is 35 adapted to slide on the tube 50 and is secured to the inner end of the end section 52 by the cross pin 57. A hole 73 in the end disk 48 of the platen permits the passage of the locking pin therethrough for 40 engagement with the ratchet wheel. Any other suitable construction may be used to provide a releasable connection between the platen shaft J and the ratchet wheel 65.

For ordinary line spacing, only one of the holes 70 in the ratchet wheel 65 is necessary, a plurality of holes being provided, so that, should the platen be disconnected from the ratchet 65, as for fractional line spacing, the pin 71 may be quickly returned 45 to connect the platen with the ratchet wheel by being entered in whichever hole 70 of the ratchet wheel that may happen to be in line with it at the time. The end of the locking pin is tapered to facilitate its engagement with the ratchet wheel. Should the end of the locking pin strike the ratchet wheel between two of the holes and fail to enter one of them, it will spring into one 50 of the holes the first time the ratchet wheel is turned by the operation of the line space lever, presently described.

K represents a line space lever, which preferably has a forwardly projecting arm provided at its front end with a handle portion 80, and having a forked rear end

81 that straddles the platen shaft and is pivoted to a bracket L by screws 82, 83 arranged above and below the platen shaft in the vertical plane thereof, so that the lever K can swing substantially horizontally. 70 The bracket L (see Figs. 4-10) is preferably formed as a single piece die casting and is disposed in the recess 29 of the carriage end plate 28 and forms a support for the various parts of the line space mechanism. 75 It is provided with an open ended slot 85, similar to the slots 37 of the carriage end plates, which receives the end section 52 of the platen shaft and permits the shaft to pass in and out of its bearing seats in 80 the end plates.

The upper edges of the carriage end plates 27, 28 are concentric with the axis of the platen shaft and the bracket L has a lip 86 which overhangs and engages said concentric upper edge of the adjacent end plate as shown in Figs. 7 and 11. The lower pivot screw 83 for the lever K is formed with a flat sided bottom extension 87 which projects into a transverse slot 88 in the 90 curved bottom of the part 29 of the carriage end plate 28 (see Fig. 11). This construction permits the bracket L to be rocked relative to the platen shaft and retains it in its proper location when the platen shaft 95 is removed. The bracket L can be turned to place its slot 85 in register with the slots 37 which will allow the bracket to remain on the carriage when removing the platen D, the platen shaft passing out through said 100 slots. If desired the bracket L and the line space mechanism carried thereby may be removed with the platen.

A line space pawl 90 is pivoted on the upper fork branch 81 of the line space lever 105 K preferably between a pair of lugs 91, Figs. 3 and 17, and projects laterally over the ratchet wheel. The free end of the pawl is pressed toward the teeth of the ratchet wheel, preferably by a small coil 110 spring 92 located in an opening in the pivot end of the pawl. This location of the line space pawl permits it to swing directly over the platen shaft and rotate the platen with less effort than if the pawl were pivoted in front of the shaft. Another important result of this location is that the paper can pass around the platen downwardly in rear of the pawl and upwardly 115 in front of it without interference therewith. The use of wider paper than usual extending out beyond the ends of the platen is thus permitted.

Preferably a detent roller 75 for fractional line spacing is journalled on the upper end of a lever 100 pivoted on a lateral stud 101 of the bracket L (see Figs. 5, 6 and 10) and the roller is pressed against the teeth of the ratchet wheel by a spring 102 which is coiled around the stud 101 with its 120 125 130

opposite ends engaging the detent lever and the rack bar G respectively, (see Figs. 3-6). This spring in addition to actuating the detent lever, also yieldingly holds the rack bar G in mesh with the carriage feed pinion H.

P represents a line space adjusting device which cooperates with the pawl 90 to cause the movement of the line space lever to produce a one, two or three line space movement of the platen. The adjusting device is preferably made from a sheet metal stamping, shown in Fig. 12, which is bent on the dotted lines, shown in said figure, 15 into the shape shown in the other figures of the drawings. This device is provided with a hole 105 by which it is pivoted on the pivot screw 82 for the line space lever K, inclines upwardly and inwardly therefrom 20 and has a backwardly bent detent portion 106 with a pointed extremity which is adapted to snap into one or another of three notches 108 on the top of the bracket L, (Figs. 4, 5, 9 and 13), for holding the device 25 in three different positions. An actuating finger piece 109 curves outwardly and forwardly above the line space lever K so as to clear the projecting edge of the paper. The adjusting device also has an inclined rear end 30 110, (Figs. 13-16), and a substantially horizontal guide edge 111 upon which the free end of the line space pawl 90 normally rests. Upon actuating the line space lever K the line space pawl 90 will move along the guide edge 35 111 and down the incline 110 into engagement with the first tooth of the ratchet wheel 65 which may be in its path, and the continued movement of the lever K will rotate the ratchet wheel and the platen until the pawl 40 contacts with a fixed stop 115 extending laterally from the bracket L and thus arrests the movement of the pawl and ratchet wheel. The extent of rotation of the platen will depend upon the adjustment of the adjusting device P. If the latter is set with 45 its detent in the front notch 108 the ratchet wheel will be turned a distance of three teeth, see Fig. 14, while by setting the device in the position shown in Fig. 16 in which its detent will be in the rear notch 108, only a one tooth movement is effected. In the middle position of the adjusting device, shown in Fig. 4, the ratchet will be 50 turned a distance of two teeth. The pawl moves the same distance in all cases and its engagement with the stop 115 limits the movement of the line space lever K and platen, and positively prevents the platen 55 from overrunning.

60 As shown in Figs. 4, 5, and 17, a leaf spring 112 secured to the rear end of the line space lever K and bearing against a rounded projection 113 on the bracket L, acts to return the lever to normal position 65 after use. When the lever is thus returned

the free end of the pawl 90 rides upwardly on the incline 110 out of engagement with the ratchet wheel 65 and onto the guide 111 of the adjusting device, leaving the platen D free to be rotated backwardly by the 70 finger wheels if desired.

R represents the paper table which, as usual, extends upwardly and rearwardly behind the platen. This table is rigidly secured to a shaft 120 journaled at its opposite ends in the rear portions 31 of the carriage end plates 27, 28. A downwardly and forwardly projecting finger 121, fixed to the left hand end of this shaft, normally engages a rearwardly projecting lug 122 on the bracket L (see Figs. 3 and 4) and holds the bracket and the line space mechanism mounted thereon in operative position. A coil spring 123, Fig. 3, at the opposite end of the shaft 120 holds the shaft and table 80 85 in the normal position.

As will be apparent from the drawings, the line space pawl 90, detent 75, adjusting device P and the supporting bracket L are all grouped around the platen shaft within a circular space of the diameter of the platen, so that the paper can project beyond the end of the platen around these various parts practically to the carriage end plate without interference with any of the parts. 90 In like manner the opposite edge of the paper can project beyond the other end of the platen around the inwardly offset parts of the end plate 27 and carriage release lever 40. Paper considerably wider than the length of the platen can therefore be used on the machine, although the carriage is no longer than the carriages on standard machines which cannot take as wide paper. 100

When the parts of the machine are in operative position the free ends of the line space lever K, adjusting device P and carriage release lever 40 all project above the line a—b and the upper edge of the paper table R projects rearwardly beyond the line c—d as shown in Fig. 4. When the rear part of the machine is lowered preparatory to encasing it for transportation, the lines a—b and c—d become horizontal with the line space lever, adjusting device, carriage release lever and paper table R in the positions shown by dotted lines in Fig. 1. 110

To condense and encase the machine, the end sections 51, 52 of the platen shaft J are pushed inwardly and there locked by turning the finger wheels as described. The inner edge of the left hand finger wheel at this time engages and moves the line space lever K inwardly so that its front end will not extend sideways beyond the vertical plane of the outer face of the finger wheel and the total length of the carriage is thereby reduced to the width of the keyboard. The carriage is now moved to bring its 120 125 130

center opposite the printing point and the cover part B of the enclosing casing is placed over the upper part of the machine and moved forwardly. This pushes the upper 5 edge of the paper table forwardly, rocking the shaft 120 and swinging the finger 121 out of contact with the lug 122 of the bracket L, which leaves the bracket free to rock on the platen shaft. The cover B is now 10 pressed downwardly and engages the front end of the line space lever, swinging it downwardly and rocking the bracket L and parts carried thereby in the same direction, (see Figs. 1 and 5). Since the act of applying 15 the cover to the machine causes the various shiftable parts mentioned to assume the positions shown in Fig. 5, there can be no danger of injury to any part by neglecting to shift it before applying the cover.

20 To restore the machine to operative position the cover is removed, when the rack bar will be automatically re-engaged with the feed pinion by its spring 102. The front end of the line space lever is then 25 lifted, which will restore the line space mechanism to operative position. The paper table will then be returned to its proper position by the spring, and the finger 121 will engage the lug 122 on its bracket L and hold the 30 line space mechanism in position.

If desired a spring could be used to restore the bracket L and parts carried thereby to normal position when the cover is removed. For machines not requiring a 35 change in position of the line space lever, the bracket L could be omitted and the parts carried thereby mounted directly on the end plate of the carriage. Also the bracket L could be mounted at the opposite end of the 40 carriage if preferred. In fact such change in location is required in machines having a line space lever with a downwardly cranked end to be operated by the thumb of the right hand.

45 I claim as my invention:

1. In a typewriting machine, a rotary platen, a line space ratchet wheel at its end, a bracket rotatable relative to the platen, a line space lever, a line space pawl, a stop 50 for the pawl, and a detent for the ratchet wheel, all operatively mounted on said bracket and movable therewith to different positions.

2. In a typewriting machine, a platen, 55 a line space lever operatively connected thereto and arranged to swing laterally for turning the platen, said lever being also mounted to tip relatively to the platen for lowering the front end of the lever out of operative position.

3. In a typewriting machine, a line space lever mounted to tip for lowering its front 60 end out of operative position, a paper table acting to normally hold the line space lever in operative position, and a cover for the

machine which acts on the paper table to automatically unlock the lever as the cover is placed on the machine.

4. In a typewriting machine, a line space lever arranged to shift from its operative 70 position for condensing the machine, and a cover for the machine and connections whereby the act of enclosing the machine shifts the adjusting lever out of its operative position.

5. In a typewriting machine, a cover therefor, a line space lever normally extending above the closed position of the adjacent part of the cover and movably mounted 80 so that when the cover is applied to the machine it moves the line space lever downwardly.

6. In a typewriting machine, a platen, a laterally movable line space lever for turning the platen, and a laterally shiftable 85 platen knob arranged to shift the line space lever inwardly when the knob is moved toward the platen.

7. In a typewriting machine, a rotary platen and shaft, a bracket removably mounted on the platen shaft and having an open slot whereby the shaft may be passed in or out of the bracket, and a line space lever mounted on the bracket.

8. In a typewriting machine, a carriage, a rotary platen detachably mounted on the carriage, a line space lever, a detachable bracket supporting the line space lever and arranged on the platen shaft between the 90 end of the platen and carriage and having an opening whereby the bracket can retain its position on the carriage, or be detached therefrom with the platen.

9. In a typewriting machine, a platen and platen shaft, a line space lever, a line space pawl, and wheel actuated thereby, and a line space adjusting lever pivotally mounted over the platen shaft to swing horizontally and having a part acting to hold the pawl 100 out of contact with the wheel for variable distances in the movement of the pawl.

10. In a typewriting machine, a platen, a line space lever and pawl, a line space adjusting device comprising a pivoted lever, a guide for the pawl, and retaining spring, all formed of one piece of sheet metal, and acting by a horizontal movement of the lever to change the line space movements of the platen.

11. In a typewriting machine, a platen and platen shaft, a line space lever and pawl, a line space adjusting device comprising a lever pivotally mounted over the platen shaft and having a line space pawl guide extending toward the platen within the space between the entering and receding ends of the paper on the platen.

12. In a typewriting machine, a platen, a forwardly extending laterally movable line space lever having its rear end mounted on 130

a rotatable support, and a cover for the machine acting to depress the front end of the lever when the cover is applied to the machine.

5 13. In a typewriting machine, a platen, a line space lever which moves laterally to turn the platen, and is mounted to swing downwardly from its normal position, a locking device normally holding the lever 10 in operative position, and a cover for the machine acting to unlock the lever and

lower it when the cover is applied to the machine.

14. In a typewriting machine, a platen, a line space lever having two motions, one to 15 turn the platen, and the other to move the lever independently of the platen to an inoperative position, and a cover for the machine acting to effect the last described movement of the lever as the cover is applied to 20 the machine.

EMMIT G. LATTA.
